BEDSPRING

Filed June 13, 1935

FIG. 1

UNITED STATES PATENT OFFICE

2,135,607

BEDSPRING

Don Carlos Travis, Kenosha, Wis., assignor to
 Simmons Company, New York, N. Y., a corporation of Delaware

Application June 13, 1935, Serial No. 26,331

7 Claims. (Cl. 5—230)

This invention relates to improvements in bed springs and has reference more particularly to an improved top construction.

The main objects of the invention are to provide a bed spring with a large surface area for adequately supporting mattresses, especially of the inner spring type; to provide a top construction which will afford such large supporting area and which will also tend to control sideway of the springs in the structure; to provide a bed spring having said adequate supporting area but which will nevertheless afford the desired soft and resilient support for a mattress; and in general, it is the object of the invention to provide an improved bed spring.

Other objects and advantages will be understood by reference to the following specification and accompanying drawing, wherein there is illustrated a bed spring embodying a selected form of the invention.

In the drawing:

Fig. 1 is a plan; and

Figs. 2 and 3 are sections on the lines 2—2 and 3—3 respectively of Fig. 1.

The bed spring illustrated in the drawing includes a top border frame 5 preferably made of angle iron, a bottom border frame 6 also preferably made of angle iron, spring supports such as indicated at 7 and axially vertical coil springs the outermost of which are designated 8 and the intermediate of which are designated 9.

The lower border frame 6 is preferably arranged with its vertical flange depending from the inner edge of the horizontal flange and the spring supports 7 are suitably secured to the vertical flange of the lower border frame by riveting or otherwise as indicated. The supports 7 preferably extend transversely of the bed spring and the coil springs 8 and 9 have their lower ends seated on and suitably tied to the respective supports.

As shown, especially in Fig. 1, the springs 8 and 9 are arranged so that they form rows of springs extending transversely of each other both in respect of spring rows extending longitudinally and transversely of the bed spring and in respect of spring rows extending diagonally of the bed spring in relatively transverse directions.

The top coils of the outermost or border springs 8 are preferably provided with loops or ears 10 which extend under the horizontal flange of the upper border frame 5, and rivets designated 11 which extend through the border frame and through said spring loops serve to securely anchor said border springs to the top border frame.

The springs arranged in rows extending transversely of the bed spring have their top coils connected by means of resilient helical springs 12 and the said top coils in the rows extending longitudinally of the bed spring are similarly connected by means of resilient helicals 13. It will be apparent that because of the anchorage of the border springs, the inner springs 9 will be resiliently supported in their properly spaced relation through the agency of said helicals 12 and 13. 10

A bed spring embodying the structure so far described may constitute a complete and operative bed spring, but for some purposes, especially for supporting a mattress of the inner spring type, it may be considered as lacking in respect of area on which to rest the mattress. 15

To provide for adequate support of inner spring and other mattresses, a top structure embodying thin, flexible, metallic straps is provided.

In this instance, the top structure includes a plurality of relatively short straps each of which is designated 14, said straps being arranged in rows overlying diagonally extending spring rows. Preferably the straps are each of such length that they extend approximately from center to center of the springs in each row. Hence the straps are arranged in rows overlying spring rows and, as clearly illustrated, the short straps are arranged substantially in longitudinal alignment. The rows of spring straps also intersect one another in accordance with the similar arrangement of the spring rows and the arrangement is preferably such that the intersection of rows of straps is located approximately centrally over the coil-springs. It is also preferably such that there is an intersection over each of the coil springs, especially in reference to the inner springs. 20 25 30 35

Where the strap rows intersect over springs, the adjacent strap ends are preferably pivotally connected together. Such connection is in this instance effected through the agency of a metallic plate 15 which has portions overlying each of the adjacent strap ends and pivoted thereto as indicated at 16. As clearly shown in Fig. 3, the pivot connection 16 between the plate and each 40 45 strap 14 is formed by punching the metal of the plate 15 downwardly through an appropriate opening 17 provided in the strap 14 and swaging the punched down metal outwardly as indicated at 18 to form an eyelet connection between the 50 respective plate portions and the strap ends.

At the periphery of the top strap structure, it is connected to the border frame by means of resilient helical coil spring connectors 19. At each corner of the bed spring, the adjacent end 55

- of a strap 14 is provided with an aperture which receives an end hook of the connecting helical 19 and the other end of the helical is also provided with a hook which engages with an aperture provided in a strap element 20 which is anchored to the border frame by means of a rivet 11 which also anchors the adjacent border spring 8 to the frame. Intermediate the corners where a pair of diverging straps 14 intersect, such strap ends may be pivoted together by eyelet means such as described for connecting the plate 15 to the respective strap ends, the eyelet then being formed out of the metal of one of the straps which is punched through an opening in the other strap. However, such connection is not important and it may be effected solely by means of an end hook of the corresponding helical 19 which may engage registering apertures in the adjacent straps ends. The helicals 19 which connect the periphery of the top strap structure intermediate its corners are also anchored to the border frame through the agency of short strap elements 20, each of which is anchored to the top border frame by means of said rivets 11.
- If desired, the axially vertical coil springs may be connected to each other intermediate their top and bottom coils by suitable connecting ties such as indicated at 21, some of which may connect the springs in the transversely extending rows and others of which may connect the springs in longitudinally extending rows.
- It will be seen that the described top strap construction is not only flexible in a vertical direction so as to follow the compression of the axially vertical coil springs, but that the rows of straps are flexible laterally owing to the pivoted connection of the respective short strap lengths which form the rows. By reason of the lateral flexibility, said strap rows may flex in localized areas when required without transmitting lateral movement over the entire length of the strap rows. This is an advantage in that it tends to reduce side sway and to confine it to localized zones where it may be incident to compression of the vertical springs and sidewise movement imparted thereto. The straps 14 provide adequate supporting area for a mattress to prevent the same from sagging between the straps and such supporting area is of course augmented by the connecting helicals 12 and 13 and by the top coils of the vertical springs 8 and 9. In one embodiment, the straps may be about $\frac{1}{8}$ of an inch in width and in the neighborhood of nine inches in length. Of course the length will be dependent upon the spacing of the springs in the rows, where it is desired that pivoted connections should be effected over each spring and upon other considerations incident to the particular construction of the bed spring in which the top structure is incorporated.
- If desired, the top strap structure may be anchored at a few places to top coils of a few of the axially vertical springs. Such anchoring may be effected by wire clip means as indicated at 21 or otherwise and because of the nearness of such points of attachment to the pivots of the respective straps, there will be no serious impairment of said lateral flexibility of the top structure.
- Changes in the described construction may be made without departing from the spirit of the invention, the scope of which should be determined by reference to the following claims, the same being construed as broadly as possible consistent with the state of the art.

I claim:

1. In a bed spring, the combination of a border frame, a plurality of axially vertical coil springs arranged and supported in transversely extending rows within said border frame, a generally flat, lattice-like top construction which is adapted to overlie the top coils of said coil springs and which is movable within reasonable limits independently of at least the greater portion of said coil springs, and means resiliently connecting said top construction to said border frame, said top construction comprising a plurality of relatively short, flexible straps arranged in rows which extend generally diagonally to said rows of vertical coil springs, the straps in each row being disposed in longitudinal alignment and said rows intersecting each other adjacent the ends of adjacent straps in each row, the adjacent strap ends at each of a plurality of said intersections being disposed in laterally spaced relation to each other, and a plurality of plate members each of which is located at one of said intersections and has portions overlapping and pivoted to each of said adjacent strap ends at that intersection. 25
2. In a bed spring, the combination of a border frame, a plurality of axially vertical coil springs arranged and supported in relatively transversely extending rows within said border frame, a lattice-like top construction overlying said spring 30 rows, and means resiliently connecting said top construction to said border frame, said top construction comprising a plurality of short flexible straps arranged in rows which extend generally diagonally to said rows of vertical coil springs, 35 the straps in each row being disposed in longitudinal alignment and said rows intersecting each other centrally over individual coil springs and adjacent the ends of adjacent straps in each row, the adjacent strap ends at each of a plurality of said intersections being disposed in laterally spaced relation to each other and overlying the top coil of the spring at that intersection, and a plurality of plate members each of which is arranged centrally over the coil spring at one of 45 said intersections and having portions overlapping and pivoted to each of said adjacent straps, whereby each of the interconnected straps may pivot freely about a vertical axis substantially independently of the other straps and the coil 50 spring at that intersection. 40
3. In a bed spring, the combination of a border frame, a plurality of axially vertical coil springs arranged and supported in transversely extending rows within said border frame, the upper coil of each of said springs being substantially flat and said upper coils being disposed in substantially co-planar relation, a generally flat, lattice-like top construction which is adapted to overlie the top coils of said springs and which is movable within reasonable limits independently of at least the greater portion of said coil springs, and means resiliently connecting said top construction to said border frame, said top construction comprising a plurality of short, flexible straps arranged in rows which extend generally diagonally to said rows of vertical coil springs, the straps in each row being disposed in longitudinal alignment and said rows intersecting each 60 other adjacent the ends of adjacent straps in each row, and means pivotally interconnecting the adjacent strap ends at each of said intersections in such manner that each of said interconnected straps may pivot freely about a vertical 65 axis. 60
4. In a bed spring, the combination of a border frame, a plurality of axially vertical coil springs arranged and supported in transversely extending rows within said border frame, the upper coil of each of said springs being substantially flat and said upper coils being disposed in substantially co-planar relation, a generally flat, lattice-like top construction which is adapted to overlie the top coils of said springs and which is movable within reasonable limits independently of at least the greater portion of said coil springs, and means resiliently connecting said top construction to said border frame, said top construction comprising a plurality of short, flexible straps arranged in rows which extend generally diagonally to said rows of vertical coil springs, the straps in each row being disposed in longitudinal alignment and said rows intersecting each 70 other adjacent the ends of adjacent straps in each row, and means pivotally interconnecting the adjacent strap ends at each of said intersections in such manner that each of said interconnected straps may pivot freely about a vertical 75 axis. 70

axis substantially independently of the other straps of that intersection.

4. In a bed spring, the combination of a border frame, a plurality of axially vertical coil springs arranged and supported in relatively transversely extending rows within said border frame, the upper coil of each of said springs being substantially flat and said upper coils being disposed in substantially co-planar relation, a generally flat, lattice-like top construction which is adapted to overlie the top coils of said springs and which is movable within reasonable limits independently of at least the greater portion of said coil springs, and means resiliently connecting said top construction to said border frame, said top construction comprising a plurality of short flexible straps arranged in rows which extend generally diagonally to, and which overlie, said spring rows, the straps in each row being disposed in longitudinal alignment and said rows intersecting each other substantially centrally over individual coil springs, the straps of each row being of such length as to extend between adjacent intersections and the adjacent strap ends at each of a plurality of said intersections overlying the top coil of the adjacent spring and being movable relative thereto, and means pivotally interconnecting the adjacent strap ends at each of said intersections in such manner that each of said straps may pivot freely about a vertical axis independently of the other straps at that intersection and of the adjacent spring.
5. In a bed spring, the combination of a border frame, a plurality of axially vertical coil springs arranged and supported in transversely extending rows within said border frame, the upper coil of each of said springs being substantially flat and said upper coils being disposed in substantially co-planar relation, a generally flat, lattice-like top construction which is adapted to overlie the top coils of said springs and which is movable within reasonable limits independently of at least the greater portion of said coil springs, and means resiliently connecting said top construction to said border frame, said top construction comprising a plurality of short flexible straps arranged in rows which extend generally diagonally to said spring rows, the straps in each row being disposed in longitudinal alignment and said rows intersecting each other substantially centrally over individual coil springs, the straps of each row being of such length as to extend between adjacent intersections and the adjacent strap ends at each of a plurality of intersections overlying the top coil of the adjacent spring and being movable relative thereto, and a plurality of plate members each of which is arranged centrally over the coil spring at each of said intersections and has portions overlapping and pivoted to each of said adjacent straps whereby each of the interconnected straps at each of said intersections may pivot freely about a vertical axis

substantially independently of the other straps and the coil spring at that intersection in order that the rows of straps shall be flexible laterally to permit lateral movement of the straps in localized areas during use of said spring.

6. In a bed spring, the combination of a border frame, a plurality of axially vertical coil springs arranged and supported in straight line rows within said border frame, the top coils of all said coil springs lying substantially in a single plane, a generally flat, lattice-like top construction which is adapted to overlie the top coils of said coil springs and which is movable within reasonable limits independently of at least the greater portion of said coil springs, and means resiliently connecting said top construction to said border frame, said top construction comprising a plurality of relatively short, flexible straps disposed in longitudinal alignment to form a plurality of straight line, intersecting rows, one of which rows overlies each of said spring rows, said strap rows intersecting each other centrally over individual coil springs, and the individual straps making up each of said strap rows being of such length as to extend between adjacent springs of the underlying row of coil springs, and means for mechanically interconnecting the adjacent strap ends at each intersection over a coil spring in such manner that each strap is movable independently of the other straps and the coil spring at that intersection.

7. In a bed spring, the combination of a border frame, a plurality of axially vertical coil springs arranged and supported in straight line rows within said border frame, the top coils of all said coil springs lying substantially in a single plane, a generally flat, lattice-like top construction which is adapted to overlie the top coils of said coil springs and which is movable within reasonable limits independently of at least the greater portion of said coil springs, and means resiliently connecting said top construction to said border frame, said top construction being made up of a plurality of short, flexible straps disposed in longitudinal alignment to form a plurality of straight line intersecting rows, one of which rows overlies each of said spring rows, said strap rows intersecting each other both centrally over individual coil springs and intermediate said coil springs, the individual straps making up each of said strap rows being of such length as to extend between adjacent springs of the underlying row of coil springs, and the adjacent strap ends at each of a plurality of the intersections overlying the coil springs being mechanically connected together by means which permits each of said straps to pivot freely about a vertical axis independently of the other straps at that intersection and of the underlying coil spring.

DON CARLOS TRAVIS.
